UNITED STATES PATENT OFFICE.

EMERICH SCHWARZ, OF CHICAGO, ILLINOIS, ASSIGNOR OF ONE-HALF TO ARTHUR E. SANDER, OF CHICAGO, ILLINOIS.

PIANO-STOOL.

1,113,696.

Specification of Letters Patent.

Patented Oct. 13, 1914.

Application filed July 11, 1913. Serial No. 778,577.

To all whom it may concern:

Be it known that I, EMERICH SCHWARZ, a citizen of the United States, residing at Chicago, in the county of Cook and State of Illinois, have invented certain new and useful Improvements in Piano-Stools, of which the following is a specification.

The essential object of this invention is to provide a piano stool containing a seat which can be raised or lowered, and which, when raised, will be in inclined position.

In the drawings, Figure 1 is a front elevation of a piano stool embodying the invention; Fig. 2 is an end elevation taken 15 at right angles to Fig. 1; Fig. 3 is a front elevation of a stool with a modified form of operating mechanism; Fig. 4 is an end elevation of the form shown in Fig. 3; and Figs. 5 and 6 are views at right angles to 20 each other of parts of the operating mechanism.

The stool comprises the longitudinal members 1 and cross members 2, suitably supported by legs 3. The seat 4 is adapted to 25 rest, when in lowered position, upon the rectangular frame composed of members 1 and 2, and when in elevated position, to be supported from said members by the operative mechanism hereinafter described. To 30 the seat 4 the angle irons 5 are secured, being slotted at 6, and pins 7, secured to the frame members 1 or 2, ride in slots 6, and in this manner the movement of the seat 4 is guided and limited. In the preferred form 35 of the invention the seat 4 is elevated by moving the lever 8 from full line position, Fig. 2, to dotted line position. Rigidly secured to said lever 8 is a metallic band or strap 9 which extends from end to end of 40 the stool, and the ends of strap 9 are received within the sector-shaped perforations 10 in the plates 11, which plates are secured to the cross members 2. The lower right-hand edge, Fig. 5 of the strap 9 seats in the 45 crotch 12 of the perforation 10, which crotch serves as a fulcrum upon which the plate or strap 9 can move, and a link 13 connects the lever 8 to an arm 14, which arm 14 is connected to a second strap 9 on the right side, 50 Fig. 2.

If the lever 8 be moved from full line position, Fig. 2, toward the dotted line position, the upper end of said lever will engage the under surface of the seat 4, and at the 55 same time the end of the arm 14 will also

engage the under surface of the seat, and as the lever 8 and arm 14 move from the oblique to or toward the vertical positions, the seat will be elevated. The distance from the bearing edge of the right-hand strap 9 to the end of the arm 14 is slightly greater than the distance from the left-hand strap 9 to the end of the lever 8; hence, when the parts have assumed the vertical position, Fig. 2, the right-end of the seat 4 is raised higher than the left end. Since the seat is usually made of wood, it is desirable to place a metal strip or reinforcement 15 upon its under surface in order to prevent abrasion of the seat by the members 8 and 14. 70

In Figs. 3 and 4 a modification is shown in which the straps 9 are turned toward each other and are adapted to rotate in opposite directions instead of rotating in unison, as in the other form of the invention. The 75 straps 9 are secured to links 16, one of which is a little longer than the other. Pivoted to link 16 at 17 are pitmen 18, which members 18 are pivoted together at 19. One member 18 carries an ear 20 bent at right 80 angles to the rest of the member, and to this depending ear 20 the link 21 is pivoted. The bell-crank lever 22 is pivoted at 23 to the bracket 24 which depends from the rectangular frame. The right side of said bell-crank 85 22 is adapted to be engaged by the operator and forced toward the left, Fig. 3, and since left arm of the bell-crank is pivoted at 25 to the link 21, it is obvious that to push the bell-crank 22 in one direction 90 will elevate the seat; whereas to move it in the opposite direction will lower the seat.

It will be observed that in the form shown in Figs. 1 and 2 there is but one lever 8, and in the form depicted in Figs. 3 and 4 but 95 one bell-crank lever 22. The bands or straps 9 which are thus actuated at one end only, same being the right end, Figs. 1 and 3, carry suitable arms 26 at the opposite ends, which arms are rotated in accordance 100 with the rotation of the bands 9 and which bear upon and support the left end of the seat 4. The bands 9 merely project into and through slots in the members 8, 14, 16, and 26, thus dispensing with the necessity for 105 set-screws or similar appliances which would be required if a round bar journaled in an ordinary bearing were used in place of the flat strap or straps 9.

It will further be obvious that sundry 110

changes in the details of construction and arrangement of parts may be made without departing from the scope of the invention.

I claim as my invention:

5 The combination with a frame of a seat movable with respect thereto, a plurality of plates secured to said frame, each plate having a sector-shaped opening, a movable strap interposed between each pair of plates and extending into the sector-shaped openings thereof and arranged to be guided

thereby, one edge of the stop resting in the crotch of said openings, and arms carried by the straps and in engagement with the seat aforesaid.

15

In testimony whereof I hereunto affix my signature in the presence of two witnesses.

EMERICH SCHWARZ.
